UNITED STATES PATENT OFFICE.

WLADYSLAW J. GAJKOWSKI, OF BUFFALO, NEW YORK, ASSIGNOR OF ONE-FOURTH TO STANISLAW Z. GRABOWSKI, ONE-FOURTH TO STANLEY J. GAJKOWSKI, AND ONE-FOURTH TO EDMOND GAJKOWSKI, ALL OF BUFFALO, NEW YORK.

GUARD FOR WIRE-DRAWING MACHINES.

Application filed May 23, 1922. Serial No. 562,986.

To all whom it may concern:

Be it known that I, WLADYSLAW J. GAJKOWSKI, a citizen of the Republic of Poland, residing at Buffalo, in the county of Erie and State of New York, have invented certain new and useful Improvements in Guards for Wire-Drawing Machines, of which the following is a specification.

My invention relates to guards for wire drawing machines, and more particularly to a guard for the reel, or what is generally known as the "wire block" of the machine.

In wire drawing machines, accidents frequently happen, such as catching the fingers or other members, or the clothing of the operator between the wire and the reel or block; other injuries being caused to the operator, due to the wire breaking and a portion of the wire on the reel becoming uncoiled and opening up so that the end of the uncoiled portion is swung outwardly by centrifugal force and slashes the operator, oftentimes resulting in disfiguring his face or causing other serious injuries.

The primary object of my invention is to provide a guard which is so constructed that it may be equally adapted for use in connection with large reels or blocks employed in machines for drawing heavy gauge wire or with small reels or blocks forming part of machines used for drawing fine or light gauge wire.

Another object of my invention is to provide a guard which can be conveniently attached to the machine and as readily removed therefrom, and in which provision is made for moving the guard away from the reel or block while attached to the bed of the machine so that the wire can be easily started on the reel.

A further object is to so mount the guard, that as soon as the machine is started, the guard may be conveniently moved inwardly into protecting position to prevent unwinding of the wire from the reel or block in the event of the wire becoming broken and also to guard against the drawing in of the fingers or other members of an operator.

A still further object is to provide a guard of simple construction, and one which is inexpensive and conveniently operated under the conditions of use necessary in a machine of the kind mentioned.

The invention consists in the novel fea-

tures of construction, and in the arrangement and combination of parts to be herein-after described and more particularly pointed out in the subjoined claims.

In the drawings:

Fig. 1 is a plan view of a portion of a wire drawing machine.

Fig. 2 is an enlarged transverse section through the machine, taken on line 2—2, Fig. 1, the reel or block being shown in elevation.

Fig. 3 is a slightly enlarged sectional elevation of the machine, the section being taken through the guard on line 3—3, Fig. 1, and looking in the direction of the arrow crossing said line.

Fig. 4 is a detached perspective view of the movable member of the guard.

Fig. 5 is a detached perspective view of the securing or fixed member of the guard.

Fig. 6 is a transverse section taken on line 6—6, Fig. 5.

Fig. 7 is an enlarged section through the guard taken on line 7—7, Fig. 1, the adjacent portion of the reel or block being shown in elevation with the position of the wires thereon in dotted lines.

Fig. 8 is a longitudinal section through the guard taken on line 8—8, Fig. 1.

The machine has a suitable frame 10 supporting a table or bed 11, on which is mounted a drawing die 12, which may be of any well known form or construction and through which the wire, designated by the numeral 13, is adapted to be drawn to reduce the diameter of the same, the wire being uncoiled from a suitable reel (not shown), or supplied to the machine in any other manner.

14 designates the reel, or what is generally known as the "wire block," which is slightly tapered upwardly and has a circumferential flange 15 at its lower end. This reel or block is provided with detachable upstanding arms 16, which are removably inserted into depressions or arm-receiving pockets formed in the upper wall of the reel or block in the usual manner, preferably four such arms being employed.

The reel is secured to a vertical shaft 17 extending downwardly through the table or bed and driven by a drive shaft 18 arranged horizontally underneath the table or bed, suitable gearing 19 being provided on said

shafts to transfer the motion and power from the drive shaft 18 to the vertical shaft 17. Suitable clutches and other mechanism (not shown) are invariably employed in wire drawing machines of this kind for stopping the rotation of the vertical shaft 17 and consequently of the reel or block, and for elevating said reel or block; but since these form no part of my invention I have not considered it necessary to illustrate such parts.

The wire 18, after being passed through the drawing die, is secured or otherwise arranged on the reel or block so that when said reel or block is rotated, it will gradually wind up the wire while drawing the wire through the drawing die and reducing the diameter of said wire. Due to the upward taper of the reel or block, the convolutions 20 of the wire around the reel or block gradually move upwardly, being so forced by the portion or convolution of the wire last wound around the reel or block. In this manner the wire is wound around the reel 25 or block and the convolutions thereof gradually moved upwardly so as to eventually encircle the arms 16 rising from the top of the reel or block, and after a number of revolutions of the reel or block, the complete or 30 desired length of wire will be coiled around the block and the arms 16. When the desired length is so coiled, the convolutions of the wire around the block are worked upwardly around the coils of wire then encircling the arms 16 so as to form a circular 35 bundle, the coils or convolutions of which may be tied together for further reduction or for the market, as the case may be.

It will be noted in Fig. 1 that the wire, in 40 leaving the drawing die, passes to the reel in a line tangentially thereto, and it is the practice of the operator to occasionally grasp the wire between the drawing die and the reel or block to determine whether the 45 drawing die is properly functioning to reduce the diameter of the wire and to ascertain the quality of the wire thus reduced. This, oftentimes, results in the operator's fingers or a portion of his garment being 50 drawn between the wire and the reel or block, and before it is possible for him to stop the machine, his arm may be drawn around the reel or block and serious injury inflicted.

To prevent such accidents, and others resulting from the breakage of the wire between the drawing die and the reel or block, my improved guard, considered as a whole, and designated by the numeral 20 is secured 60 to the table or bed of the machine and positioned in close proximity to the reel or block, with a portion of the guard overhanging the flange 15, the overhanging portion of the guard being provided to prevent the uncoiling 65 of the wire in the event that the wire

becomes broken between the drawing die and the reel or block, such uncoiling being particularly prevented since the guard extends a considerable distance circumferentially along the surface of the reel or block 70 and overlies the circumferential flange thereof over an extended area.

The guard, in its more restricted sense, or considered as a guard-device, comprises a fixed or securing member 21 and a movable 75 or guard member 22, the fixed or securing member being bolted or otherwise fastened to the table or bed 11, but preferably fastened in the manner shown in Figs. 1 and 2, in which 23 designates hook bolts having 80 the ends of their hook portions entered in depressions 24 formed in the fixed or securing member 21 and their shanks extending down through the table or bed and through a transverse bar 25, nuts 26 being threaded 85 thereon and bearing against said bar.

The fixed or securing member comprises a flat body portion 27 having at opposite sides upstanding flanges 28 provided with inwardly overhanging portions 29 along a portion 90 of their lengths and with inwardly-directed terminals or stops 30, 31 at opposite ends. The inwardly overhanging portions 29 form guide grooves 32, while the terminals or stops 30 close the outer ends of said guide 95 grooves. The inwardly overhanging portions 29 extend rearwardly from the front end of the fixed or securing member 21, or more particularly from the inwardly-directed terminals or stops 30 at the front ends of the flanges 28, the inner ends of said inwardly overhanging portions terminating a distance 100 from the inwardly-directed terminals or stops 31 at the rear ends of said flanges so as to provide openings 33 between said terminals or stops and the inner ends of the overhanging portions 29.

A transversely elongated opening 34 is formed in the flat body portion near its rear end, and at opposite ends of said opening 110 are trunnion pockets 35 which receive the trunnions 36 of a roller 37 rotatably arranged within said transversely elongated opening and extending slightly above the upper surface of said flat body portion. 115 Said flat body portion is provided with an elongated depression 38, which extends forwardly from a point near the transversely elongated opening 34 to the front edge of said flat body portion. The fixed 120 or securing member is preferably constructed of iron or other heavy material and is retained in position on the table or bed 11 by its weight and by the hook bolts 23.

At opposite sides of the fixed or securing 125 member 21, supporting arms 39 are pivotally secured, said arms, in preferred form, being constructed of flat metallic material pivotally fastened at their front ends to said fixed member and extending rearwardly there- 130

from, the rear portions being at right angles to the front portions thereof and resting upon the circumferential flange 15 of the reel or wire block 14.

- 6 The movable or guard member of the guard device comprises a segmental body portion 40, curved to conform to the curvature of the reel or wire block, and a retainer portion 41 extending forwardly from the 10 same, said retainer portion being substantially rectangular and of a width to pass between the inwardly overhanging portions 29 of the upstanding flanges 28 on the fixed member 21. At opposite sides of said retainer portion, at the forward end thereof, laterally projecting trunnions or pivot projections 42 are provided and a distance in rear of said trunnions or pivot projections said retainer portion is provided with two 20 flat retainer lugs 43, both to be fitted into the guide grooves 32 of the fixed member under certain conditions, to be hereinafter explained. Under other conditions, said flat retainer lugs are positioned directly in front 25 of the inwardly-directed terminals or stops 31 of said fixed member, and when the retainer portion 41 of the movable or guard member is positioned, as last described, locking means, associated with said retainer 30 portion, is adapted to lock said movable or guard member against movement. Said locking means comprises a handle 44 pivoted to the front end of said retainer portion 41 and having lock fingers 45 extending downwardly and adapted to enter depressions 46 in the fixed member 21, said depressions being at opposite sides of the elongated depression 38 formed in said fixed member. Said elongated depression provides sufficient 35 clearance to permit the hand or fingers of the operator to quickly and conveniently grasp the handle 44. At one end of the segmental body portion 40 a combined rest and guide element 47 is provided, said element 40 being continued along the true curvature of the segmental body portion and being gradually curved downwardly, as at 48, and terminating in a flat rest portion 49 which bears against the top of the table or bed 11. 45 The segmental body portion 40, therefore, is supported at one end by the combined rest and guide 47, and it is also supported at suitable points between its ends by the supporting arms 39 extending inwardly from 50 the fixed member 21.

As clearly shown in Fig. 2, the retainer portion 41 is in a plane beneath that of the segmental body portion 40, and said segmental body portion is provided with notches 50 on its under side which receive the flat rear portions of the supporting arms 39, opposite walls of said notches serving as stops to prevent lengthwise movement of said segmental body portion 40. Said segmental body portion is also provided along its inner

edge with an overhanging flange 51, which is positioned over the circumferential flange of the reel or block and spaced therefrom. This overhanging flange and the inner wall 70 of the segmental body portion from which it extends, taken with the circumferential wall of the reel or block and the upper face of the circumferential flange of said reel or block, forms a rectangular space between 75 the guard and the reel or block.

It is to be noted that the inner edge of the overhanging flange 51 is spaced a sufficient distance from the circumferential surface of the reel or block to permit the wire 80 as it extends from the drawing die to the reel or block enters the space between the latter and the guard, near one end of the guard, and for this purpose the segmental body portion 40 has a transverse opening 52 85 therethrough which is open at the top and provided with a retainer flange 53 at one side of said opening, said flange overhanging one of the side walls of the opening, and having its edges beveled or rounded, as 90 at 54.

Overhanging the opening 52 with its outer edge in close proximity to the edge of the retainer flange 53, is a latch or pivoted retainer 55, which has a weight 56 at the opposite side of its pivot, the weight being in the form of a long arm retained within a groove 57 arranged lengthwise in the upper face of the segmental body portion. The pivot of said latch or retainer 55 extends transversely through said segmental body portion and said weight tends to keep said latch or pivoted retainer elevated and in line with said retainer flange 53 so that a 95 guarded wire passage or opening is formed 100 through said segmental body portion, or what may be termed the guard proper. The latch or pivoted retainer may be said to serve as a pivoted top wall for said wire 105 passage or opening.

Secured to the top of the guard, above the latch or pivoted retainer 55 is a guide plate 58 having a groove 59 at its under side, into which the weight or arm 56 may swing when the latch or pivoted retainer is depressed, opposite side walls of said groove 59 serving to guide said weight or arm and prevent lateral swaying movement in the event that the pivot, or the opening through which the pivot is passed, becomes worn. A guarded wire passage or opening of this kind, enables the wire to be placed in the opening from the top, as it is simply necessary to lay the wire in position at the end of the latch or pivoted retainer and press downwardly. 115 This will swing the latch or pivoted retainer downwardly and allow the wire to pass between the end of the same and the retainer flange 53, and as soon as the wire 120 has passed between the two, the latch or 125 pivoted retainer may be returned to its original position, the weight or arm 56 being retained in the groove 59. This will hold the wire in position, and as soon as the wire 130 has passed between the two, the latch or

pivoted retainer will automatically close and retain the wire in the opening or wire passage.

In a guard of this kind it is necessary that clearance be provided between the segmental body portion and the edge of the circumferential flange 15 on the reel or block, and when winding fine wire onto the reel or block it is possible that the wire will pass downwardly over the flange. To prevent this, the segmental body portion is provided with pivoted retainers 60, which are spaced apart suitable distances along the segmental body portion, said retainers comprising pivoted members fastened into grooves 61 in the under side of the segmental body portion. To prevent these retainers swinging downwardly beyond certain limits, retainer plates 62 are secured to the under side of said segmental body portion, said plates extending across the grooves 61 and being fastened at opposite sides of said grooves by screws 63, or otherwise.

It is to be noted that the drawing die 12 is positioned on the table or bed 11 in front of or in a plane forward of the reel or wire block 14; but in some machines, and more particularly machines designed for drawing heavy gauge wire, the drawing die is disposed at one end of the table or bed a distance from the reel or block, and when my improved guard is employed in a machine of this kind, the wire passes from the drawing die to the reel or block, as for example illustrated in dotted lines at 64, the wire passing underneath the combined rest and guide 47 instead of through the guarded wire passage or opening 52.

The guard, when positioned as shown in Fig. 1, permits the operator to test the wire after having passed through the drawing die, without liability of having his fingers pinched between the wire and the reel or block or being otherwise injured, and in the event that the wire becomes broken between the reel or block and said drawing die, only so much of the free end of the wire as may be exposed between the ends of the guard will be able to swing outwardly by centrifugal force, and even this portion of the wire will be drawn inwardly toward the reel or block while passing underneath the overhanging flange 51, which will prevent the wire from swinging out to cause damage to the operator stationed at the front of the machine.

While I have herein described the guard as comprising a fixed member 21 and a movable member 22, the fixed member, in reality, serves as a means for positioning, guiding and retaining the guard proper, which consists of the movable member. Therefore, in its broader sense the movable member may be considered the guard while the fixed member, as particularly described hereinbe-

fore, may be considered a means for securing, guiding, and retaining the guard on the table or bed in desired relation to the reel or block.

When the guard, considered as the part 22, is in protecting position, as shown in Figs. 1 and 2, it is in close proximity to the reel or wire block and has its overhanging flange 51 positioned above the circumferential flange 15 of said reel or block, and in this position, prevents injury to the operator under all operating conditions. At certain times in the operation of this machine, it is desirable to provide a greater clearance between the guard and block than provided when the guard is in protecting position, and for this reason the guard is movable away from the reel or block to enable the latter to be raised or to permit of more readily applying the end of the wire to be coiled around the reel or block to the latter, and for other purposes. To accomplish this, the operator will grasp the handle 44 and swing the same upwardly on its pivots, with the result that the lock fingers 45 will become withdrawn from the depressions 46 in the fixed member 21, or combined retainer and guide as it may be termed. By then drawing the handle forwardly, the trunnions or pivot projections 42 will be moved forwardly in the guide grooves 32, while the flat retainer lugs 43 will move underneath the overhanging flanges 29 from their positions between the inner ends of said flanges and the inwardly-directed terminals or stops 31, the roller 37 providing a rolling support for the guard, which will permit the ready outward movement of the same. When the guard is moved forwardly in this manner, sufficient clearance is provided between the guard and the reel or block for all purposes of operation, other than the actual winding of the wire onto the reel or block.

When moving the guard into protecting position, it is simply necessary to again grasp the handle 44 and shift the guard rearwardly, until the lock fingers 45 of the handle again engage the depressions 46 in the combined retainer and guide, said lock fingers retaining the guard in protecting position. During the forward and rearward movements of the guard, the latter is supported by the supporting arms 39 in addition to be supported by the roller 37 and the combined rest and guide 47.

When it is desired to remove the guard without removing the combined retainer and guide from the table, the guard may be swung upwardly on the trunnions or pivot projections 42 so as to cause the flat retainer lugs to pass up through the openings 33. By then forcing the pivoted end of the guard rearwardly to bring the trunnions or pivot projections 42 in line with the open-

ings 33, the entire guard may be lifted from the machine.

Having thus described my invention, what I claim is:—

5 1. A guard of the kind described, comprising a segmental guard member, and a securing member to which said guard member is pivotally and slidably secured.

10 2. The combination with a wire block, of a segmental guard member in protecting relation to said block and having a guarded wire passage therethrough, and means for securing said guard member to an immovable part adjacent said wire block.

15 3. In a wire drawing machine, the combination with a table and a rotatable wire block, of a securing member detachably fastened to said table adjacent said wire block, and a segmental guard in protective relation 20 to said wire block and having an extension slidably connected to said securing member.

25 4. In a wire drawing machine, the combination with a table and a wire block rotatable above said table, of a securing member on said table adjacent said wire block, a segmental guard co-operating with said block and pivotally and slidably connected to said securing member, and co-acting means on said guard and securing member to lock 30 said guard in protecting position.

35 5. A guard for wire blocks comprising a segmental guard member having a forward extension between its ends equipped with pivot projections at its front end, and a fixed member to which said guard is pivotally secured, said guard having a wire passage between one end thereof and the forward extension thereon.

40 6. A segmentally formed guard for wire blocks provided with a transverse opening, a flange overhanging one of the walls of said opening and a pivoted retainer overhanging the other wall of said opening and having its edge in contact with said flange.

45 7. A guard for wire blocks having a segmental guard member provided with a transverse opening and a pivoted retainer latch forming one of the walls of said opening.

50 8. A guard for wire blocks comprising an elongated guard member having a transverse opening therethrough, and a weighted pivoted retainer latch closing one side of said opening.

55 9. A segmental guard having a transverse opening therethrough provided with an overhanging flange at one of its side walls, a pivoted retainer latch extending over said opening from the other side wall thereof, and an arm extending in the opposite direction and serving as a weight to retain said pivoted retainer latch in closing position.

60 10. A segmental guard for wire blocks having a transverse opening therethrough, a portion of the top wall of which is pivotally arranged, said guard having an elongated

gated depression and an arm serving as a weight extending from said pivoted wall and normally entered in said elongated depression, and a guide plate secured to said guard overlying a portion of said pivoted wall and a portion of said arm.

70 11. A guard comprising a segmental body portion having a forwardly extended retainer portion, a handle pivotally secured to the front end of said retainer portion, a 75 securing member to which said retainer portion is slidably secured, and co-acting means on said retainer portion and said securing portion for locking said segmental body portion at the innermost point of its movement 80 with reference to said securing portion.

12. A guard device comprising a securing portion adapted to be fastened to a fixed portion of a machine and having a supporting roller therein and guide grooves at opposite marginal portions thereof, a guard 85 provided with pivot projections adapted for slidable and rotatable movements in said guide grooves, and means for locking said guard in position on said securing member. 90

13. In a wire drawing machine, the combination with a table and a wire block rotatable above said table, of a segmental guard, a securing member to which said guard is pivotally and slidably secured, said securing 95 member having depressions in its upper face, and hook bolts passed through said table and having the ends of its hook portions entered in said depressions.

100 14. A guard comprising a securing member having a flat body portion, upstanding flanges at opposite sides provided with inwardly overhanging portions and inwardly-directed terminals at opposite ends of said flanges, the inwardly-directed terminals at the rear ends of said flanges being spaced from said inwardly overhanging portions to provide openings between the two, a segmental guard having a forwardly extending retainer portion provided at its front end with pivot projections and at opposite sides with flat retainer lugs spaced from said pivot projections, said pivot projections being slidably and rotatably retained underneath said inwardly overhanging portions and said flat retainer lugs being positioned beneath said openings.

105 110 115 120 125 130

15. In a wire drawing machine, the combination with a table and a wire block rotatable above said table, of a securing member secured to said table and having a flat body portion provided with a transversely elongated opening and trunnion pockets at opposite ends of said opening, a roller having trunnions at opposite ends fitting said pockets and arranged to extend above the upper surface of said body portion, said securing member having inwardly opening guide grooves, a segmental guard provided with a forwardly extending retainer portion

- 6
- having pivot projections at its front end and flat retainer lugs at opposite sides spaced from said pivot projections, said pivot projections being slidably and rotatably retained in said guide grooves and said flat retainer lugs being positioned in rear of said guide grooves but movable thereinto, and means extending from said securing member to support said segmental guard.
16. The combination with a wire block having a circumferential flange at its lower end, a segmental guard positioned in closely-spaced relation to the edge of said circumferential flange and having an overhanging flange above and spaced from said circumferential flange, the edge of said overhanging flange being spaced from the circumferential surface of said wire block, and pivoted retainer elements on the under side of said guard bearing against the upper face of said circumferential flange to prevent coils of wire passing over the edge of said circumferential flange.
17. The combination with a wire block having a circumferential flange, a securing member in fixed relation to said block and having supporting arms extending therefrom and adapted to bear against the upper side of said circumferential flange, and a segmental guard provided with a forwardly extending portion slidably and pivotally connected to said securing member, said segmental guard receiving support from said supporting arms.
18. The combination of a wire block, and a segmental guard co-operating therewith and having a guarded wire passage therethrough arranged tangentially to said block.

In testimony whereof I affix my signature.

WLADYSLAW J. GAJKOWSKI.
